UNITED STATES PATENT OFFICE.

HENRY G. LYKKEN, OF MINNEAPOLIS, MINNESOTA.

MEANS FOR CONSTRUCTING CONCRETE SURFACES.

Application filed March 5, 1923. Serial No. 622,718.

This invention relates to the method of and apparatus for spreading and finishing concrete to form horizontal or approximately horizontal surfaces, and includes among 5 its objects the following: to improve upon existing methods of working concrete; to provide a method whereby concrete surfacing may be laid quickly and accurately to a predetermined form; to provide apparatus 10 for the efficient and accurate laying and smoothing of concrete and other surfaces; to provide, in an apparatus of the character referred to, means for varying the same so as to produce surfaces of predetermined selected forms; to provide adjustable means 15 for varying the form of this apparatus so that the cross-sectional shape of the surface being laid may be varied as desired; to provide adjustable means for varying the thickness 20 of the surfacing material being spread upon the surface being covered; and such further objects, advantages and capabilities as will later more fully appear.

My invention further resides in the combination, construction and arrangement of parts illustrated in the accompanying drawing, and, while I have shown therein what is now considered a preferred construction in accordance with this invention, I desire 25 the same to be understood as illustrative only and not as limiting said invention.

In the drawings annexed hereto and forming a part hereof, Fig. 1 is a fragmentary plan view of a construction embodying the 30 various features of my invention. Fig. 2 is a fragmentary longitudinal section substantially along the plane indicated by the line 2—2, Fig. 1. Fig. 3 is a fragmentary vertical section substantially along the plane 35 indicated by the line 3—3, Fig. 2. Fig. 4 is a fragmentary front elevation as indicated by the line 4—4, Fig. 2. Fig. 5 is a fragmentary cross-sectional elevation whose position is indicated by the line 5—5, Fig. 2. 40 Fig. 6 is a reduced plan view showing the apparatus and means for propelling the same along a surface upon which concrete is being laid.

Referring more in detail to the annexed 50 drawings, numeral 1 designates a plurality of elongated flat members having their edges turned up to form flanges which abut corresponding flanges of adjacent members. As shown in Fig. 2, these members 1 are 55 straight throughout the major portion of their length having a very small upturn at

the rear end as shown at 2, and a longer upturn at the forward end as shown at 3. The flanges 4 of the members 1 are perforated for the reception of tie-rods 5, by 60 means of which the members 1 are held closely adjacent each other so that the lower face of the apparatus will be quite smooth and will not when drawn over plastic concrete leave appreciable lines thereon. Secured to each of the elongated members 1, near their forward and rearward ends, are upright arms 6 which are rigidly secured in place by appropriate means such as rivets, or by spot welding. These arms 6 are preferably provided along their edges with flanges to stiffen the same and prevent them from becoming distorted under lateral pressure. Each arm 6 is connected with its next adjacent arm by a suitable adjusting 70 means 7 such as a turn-buckle arrangement whereby the angle between the arms 6, and consequently the angle between the members 1, transversely, may be adjusted as desired. By a proper adjustment of these members 80 the under surface of the apparatus may be made to have a crowned cross-section such that water can be drained from the center of a roadway toward the sides thereof. It is of course understood that this apparatus 85 may be used to construct flat concrete surfaces as well as those which are crowned. The present illustration shows this apparatus being used for the formation of a flat roadway and it will be noted that side members 90 are used to prevent lateral spreading of the concrete mixture, but the present apparatus does not rest on and is not supported by the side members, the sole function of which is to limit the lateral spread of the concrete. 95

Screeed members comprising U-shaped bars 8 and transverse hoe-like members 9 are mounted by means of members 10 adjacent the forward ends of members 1, and may be adjusted by means of bolts 11 which may 100 be screwed to the brackets 12 to vary the height of the members 9, varying the adjustment of these screeed members to vary the amount of plastic material which is permitted to remain in front of the smoothing and packing elements 1 and will therefore vary the thickness of the concrete or like material laid. By reference to Fig. 4 it will be seen that the members 9 overlap at their edges so that there will be a substantially smooth surface prepared for the members 1 to travel over.

In Fig. 6 is shown manual means for advancing this paving apparatus over the surface being laid, the same comprising a hand-wheel for rotating a shaft carried by the paving apparatus which shaft carries upon its opposite ends a pair of drums, around which are wound cables whose ends are firmly anchored alongside the pavement. As the hand wheel is turned the shaft is rotated and the cables pass over the drums in such a manner as to cause advancement of the apparatus, as will readily be understood. This mechanism is merely typical of any mechanism which may be used to cause the apparatus to move forwardly and which may include an engine resting upon the apparatus and causing the same to be propelled. It might also include a single engine fixed in the roadway ahead of the apparatus or a pair of engines located at the sides of the roadway or the like. Various other means for propelling the apparatus will suggest themselves to one skilled in the art without their being suggested herein. Ordinarily the weight of the forms will be sufficient to mold, compact and knead the concrete to a uniform consistency and true contour, while the forward movement floats and works the surface to a uniform condition. However, if it is found that the weight is insufficient, in any particular case, it will be an easy matter to place additional weight upon the top of the form, thereby securing all the weight essential for properly shaping and conditioning the concrete or the like.

Due to the length of the form and the means for gradually elevating and depressing the same at will, and due to the fact that the position of the form is unaffected by any settlement of the side curb, dips or waves, which are common in connection with prior methods of construction, are obviated.

With the present apparatus and method, all the work of screeding or striking off the concrete is accomplished in the same operation as that of smoothing the surface, i. e., by moving the sliding form forwardly on the concrete, the adjustable screed striking off the concrete to the exact contour desired. The adjustability of the screeds permits a gradual lifting or depression of the surface to produce the desired contour of the roadway. It is also within the purview of this invention that the machine may be provided with vibrating means to produce a vibratory or tamping effect. It is not the intention to limit the use of this machine to the laying of a mixture of Portland cement, sand, and coarse mineral aggregates, but the same may be used for the laying of any plastic material such as a mixture of tar, asphalt and mineral aggregate, and other similar materials.

The apparatus of the present invention can also be used in forming curved concrete sur-

faces such as turns in roadways, in the construction of which the side elements are set flush with the top of the pavement, and, as the apparatus moves forwardly, the screed members are elevated progressively from the inside of the turn to the outside thereof to form a bank. As the apparatus starts to leave the tangent, it is gradually flattened out so that on the curve the slope will all be in one direction, i. e., toward the inside of the curve. On leaving the curve and starting on a new tangent, the form is gradually again brought back to the proper crown so that drainage will be toward both sides of the roadway.

It is of course understood that the specific description of structure and methods set forth above may be departed from without departing from the spirit of my invention as set forth in this specification and the appended claims.

Having now described my invention, I claim:—

1. A structure of the character described comprising a composite surface former having a plurality of elongated narrow elements, flat upon their under side and having their forward ends bent upwardly, means for holding the elements in contact laterally and means pivotally adjustable upon the upwardly bent portions for spreading plastic material in front of the elongated members.

2. A structure of the character described, comprising a composite surface former having a plurality of elongated narrow elements, flat upon their under side and having their forward ends bent upwardly, means for holding the elements in contact laterally and means pivotally adjustable upon the forwardly bent portions for spreading plastic material in front of the elongated members, and means for adjusting the spreading means to vary the depth of material.

3. A paving apparatus comprising a plurality of elongated surfacing members arranged parallel to the direction of movement of the apparatus, means for varying the angular relation of each member and its adjacent member at several longitudinal portions of said members, screeding means in front of and supported by said surfacing members comprising a plurality of adjustable screeding portions, and means for varying the angular relation between said portions and between said portions and the surfacing members, the entire apparatus being supported solely on the material screeded and surfaced by it.

4. A paving apparatus comprising a facing member consisting of a plurality of flat faced narrow elements paralleling the direction of movement of the apparatus, means for connecting said elements to form their faces into a smooth composite surface,

a screed spaced well in front of said member, means for adjustably supporting the screed on said member, and means for varying the dihedral angles between said faces, 5 the last said means being well spaced from the connecting means to cooperate therewith to hold the surfacing member rigidly in a pre-adjusted shape.

5. In a paving apparatus, a surfacing member comprising a plurality of longitudinal elements having flat faces, means for connecting said elements, and means spaced apart from the connecting means for varying the dihedral angles between said faces, 10 15 the two said means being adapted to permit the contour of said member to be varied from concave to convex.

6. A paving apparatus adapted to surface a plastic roadway as it moves along the road comprising a surfacing means spanning the width of the roadway and supported entirely by the plastic material, means for varying the contour of the surfacing means, screeding means in front of the surfacing 20 25 means and connected therewith, and means for supporting the screeding means entirely on the plastic material, the last said means being further adapted to vary the contour of the screeding means.

30 7. An apparatus for surfacing plastic ma-

terial comprising a surfacing member supported entirely on the material being surfaced by it, means for varying the contour of said member, screeding means supported on said member, and means for varying the 35 contour of the screeding means, the two varying means being cooperable to cause the screeding means to be varied as the contour of the surfacing member is varied.

8. A paving apparatus comprising a surfacing member formed of a plurality of long, narrow, flat faced elements having upstanding lateral flanges, means for connecting said flanges together to form a composite smooth surface on the surfacing member, upstanding projections on said element, adjustable means for connecting said projections for varying the contour of the surfacing member and for rigidly locking the surfacing member in a plurality of shapes, 40 45 the surfacing member being adapted to be supported entirely on and by the plastic material which it surfaces, screeding means disposed considerably in advance of the surfacing member, and means for adjustably supporting the screeding means on the surfacing member.

In witness whereof, I hereunto subscribe my name to this specification.

HENRY G. LYKKEN.
